RAKER CONTROL

Harry R. Knittle, Catawissa, Pa.

Application November 1, 1950, Serial No. 193,350

1 Claim. (Cl. 110—32)

This invention relates to a coal-fired furnace, and more particularly to a thermostatically-controlled grate for the furnace.

The object of the invention is to provide an automatic, thermostatically-controlled mechanism for disconnecting the operation of a furnace grate when the hot coals in the fire box reach the grate and which starts the operation of the grate when an ash bed fills up on the grate whereby the ashes fall into the ash pit.

Another object of the invention is to provide a mechanism that will stop the agitation of the grate when the hot coals in the fire box approach the grate to thereby eliminate the waste of fuel and increase the fire box efficiency.

Still another object of the invention is to provide a mechanism which will allow agitation of the grate when an excess of ashes accumulate in the fire box, the mechanism being adjustable so that the mechanism can be set to operate within a predetermined temperature range, if desired.

A further object of the invention is to provide a grate-control mechanism which is extremely simple and inexpensive to manufacture.

Other objects and advantages will be apparent during the course of the following description.

In the accompanying drawings forming a part of this application, and in which like numerals are used to designate like parts throughout the same:

Figure 1 is a side elevational view of a conventional fire box having the mechanism of the present invention installed thereon, and in a locking position;

Figure 2 is a fragmentary side elevational view of the grate-actuating mechanism in an unlocked position;

Figure 3 is an enlarged vertical sectional view taken at an angle of 90° from the views shown in Figures 1 and 2, and illustrating the thermostatic control for the mechanism;

Figure 4 is a view similar to Figure 3, but showing the parts in a locked position;

Figure 5 is a fragmentary projection of Figure 4, illustrating the grate arm movement in an unlocked position;

Figure 6 is a sectional view showing the manually operable means for adjusting the mechanism.

Referring in detail to the drawings, the numeral 10 designates a conventional furnace which is provided with a fire box 11, Figure 1, and arranged in the bottom of the fire box 11 is the usual movable grate 12. The grate 12 is mounted on rollers or wheels 14, so that the grate 12 can be readily agitated or reciprocated back and forth to thereby empty the ashes that accumulate therein. For conveying coal to be burned from a suitable bin (not shown) to the fire box 11, an inclined conveyor tube 15 is provided. The conveyor tube 15 has a gravity feed discharge chute connected to its upper end so that the coal will be directed into the fire box 11. A motor 17 is provided for rotating the conveyor tube 15. The motor 17 is supported on a bracket 18 which may be secured to the outside of the furnace 10, and the motor 17 serves to drive

2

an endless belt 19. The belt 19, Figure 1, serves to operate a gear box 20, and the gear box 20 serves to rotate a small gear 21. The gear 21 is arranged in meshing engagement with a large gear 22, and the gear 22 is secured to the conveyor tube 15. Thus, upon energization or actuation of the motor 17, the conveyor tube 15 will be rotated so that coal can be conveyed from a suitable bin or reservoir upwardly, then through the discharge chute 16 and into the fire box 11.

Secured to the exterior of the furnace 10 is a support member 23, and a pin 24 pivotally connects a counterweight or actuating or controller bar 25 to the support member 23. Projecting from the raker bar 25 and secured thereto or formed integrally therewith is an arm 26. It will be noted from Figures 1 and 2 of the drawings, that the arm 26 is arranged angularly with respect to the controller bar 25. Rotatably supported by the arm 26 is a wheel 27, and the wheel 27 is adapted to be selectively engaged by or contacted by a cam 28 which is secured to the exterior of the conveyor tube 15. The gear box 20 is secured to and supported on a bracket 29, and the bracket 29 is secured to the exterior of the furnace 10.

A pin 30 pivotally connects a link 31 to the arm 26, and an L-shaped element 33 has one end pivotally connected to the other end of the link 31 by a pin 32. The connecting element 33 serves to rotate a driven shaft 34. A connecting rod 35 (broken lines in Figure 1) has one end pivotally connected to the link 31 by a pin 32, while the other end of the connecting rod 35 is pivotally connected to the grate 12 by a pin 36.

The numeral 37 designates one of the vertical walls of the furnace 10, Figure 3, and the wall 37 is provided with an opening 38. Secured to the wall 37 is a bracket 39, the bracket 39 being arranged contiguous to the opening 38, and the bracket 39 being secured to the wall 37 by suitable securing elements, such as bolts or screws 40. Projecting inwardly from the bracket 39 and extending into the furnace 10 is an ear or arm 41. A thermal unit or thermostat 42 in the shape of a spiral or coil has one end connected to the inner end of the ear 41 by a suitable securing element, such as a rivet 43. The thermostat 42 is adapted to expand or contract, depending upon the temperature conditions within the furnace.

Extending from the other side of the bracket 39 and secured thereto or formed integrally therewith is an ear or arm 44. A lever 45 is provided, and the lever 45 includes an upper section 46 which is provided with an inclined surface 47 for a purpose to be later described. The upper section 46 is pivotally connected to a lower section 48 by means of a pin 49, there being a pivot pin 50 pivotally connecting the lower section 48 to the outer end of the ear 44.

A spring member 51 has one end connected to the lower section 48 by a rivet or screw 52, while the other end of the spring member 51 is connected to the upper section 46 by a rivet or screw 53.

Connected to the free end of the thermostat 42 is a tube 54. The tube 54 is hollow and is connected to the thermostat 42 by a rivet or screw 55. Mounted for telescopic movement into and out of the tube 54 is a stem 56, and the stem 56 has its outer end connected to the lower section 48 by a pivot pin 57. The stem 56 is provided with a threaded portion 58 for a purpose to be later described. The tube 54 extends through an opening 59 in the bracket 39.

For moving the stem 56, a knurled knob 60 is provided. The knurled knob 60 includes an annular collar 61 which rides in a slot 62 that is formed in a clip 63. The clip 63 is secured to the tube 54 by suitable securing elements, such as rivets or screws 64. Thus, by rotating the knurled knob 60, the stem 56 can be adjusted or moved

into and out of the tube 54 so that the mechanism can be adjusted, whereby it will operate at any desired temperature.

In use, the motor 17 is actuated to drive the belt 19, and the gear box 20, whereby the gear 21 rotates. Since the gear 21 meshes with the gear 22, the conveyor tube 15 will be rotated so that coal will be conveyed from a bin upwardly into the discharge chute 16 and then into the fire box 11. Normally, the coal falls onto the grate 12, and the grate 12 is constantly being agitated so that the ashes will tumble off through the grate 12 into any suitable receptacle. This agitation of the grate 12 is brought about as follows: The conveyor tube rotates, whereby the cam 28 selectively engages the wheel 27 so that the link 31 is moved downwardly elevating the weight arm 26 and upon continuous travel of the cam the weight arm 26 returns the roller 27 providing a back and forth movement. This movement of the link 31 causes oscillation of a driven shaft 34 which is located within the furnace 10, and the connecting rod 35 causes the grate 12 to move back and forth so that accumulated ashes will be emptied from the grate.

It will be seen from the drawings that the back-and-forth movement of the link 31 is caused only when the temperature in the vicinity of the grate is not too high. That is, if the coals have not worked themselves down onto the grate 12, the grate 12 will be continuously agitated, and Figures 2, 3 and 5 show the position of the parts when the grate is being agitated. Thus, if there is no excessively high temperature in the vicinity of the thermostat 42, the thermostat 42 will be in its contracted position, so that the upper section 46 of the lever 45 will be pivoted out of the way of the controller bar 25, whereby the controller bar 25 will be free to pivot as the cam 28 engages the wheel 27. When hot coals are on the grate 12, the grate 12 will stop moving, so that there will be no wastage of hot coals or fuel. Thus, when the temperature of the grate 12 gets too high, the thermostat 42 expands to cause the tube 54 and the stem 56 to move so that the lever 45 will move into the Figures 1 and 4 position. Therefore, the controller bar 25 will be unable to pivot, and the wheel 27 will be arranged sufficiently spaced from the cam 28 so that the cam 28 will not engage the wheel 27, whereby the grate 12 will not be agitated until the temperature in the vicinity of the thermostat 42 again drops.

The element 33 may have a suitable ratchet wheel connected thereto. An ash pit is arranged below the traveling grate 12. The temperature-actuated element may be constructed so that either a rotary or rectilinear motion may be imparted to the shaft to which it is connected. The assembly of the present invention can be readily attached to existing furnaces without materially changing the furnaces. There are no electrical circuits which are a potential source of trouble. Also, none of the parts comes into contact with the fire in the furnace, so that they are not subject to being burned out. The assembly needs no power to operate, and the assembly can be supplied as a control for new furnaces, or can be sold to owners of furnaces now in use, where the present control is not satisfactory. The assembly of the present invention is of simple construction, positive in action, and will have or

cause a minimum amount of trouble or maintenance. When the temperature in the vicinity of the thermostat 42 is sufficiently low, the pivoted lever 45 will be moved away from engagement with the controller bar 25, so that the controller bar will be free to move whereby the grate 12 will be agitated. This agitation of the grate 12 will cause the ashes to be emptied or removed so that the fire or hot coals will move closer to the grate, thereby increasing the temperature of the grate and of the ash pit. When this temperature gets sufficiently high, the thermostat 42 reverses or contracts, so that the upper section 46 of the lever 45 moves back into engagement with the controller bar 25. It will be noted that the lever 45 is pivoted at 49, and the spring member 51 connects the upper and lower sections of the lever 45 together. This spring member 51, together with the tapered or inclined surface 47, allows the controller bar 25 to return to its non-operating position when the lever 45 has been pulled into engagement before the controller bar 25 has returned to that position. The spring 51 then forces the lever 45 back into engagement. The temperature at which the instrument operates can be adjusted by changing the length of the tube 54 and stem 56 by means of the knurled knob 60.

I claim:

In combination with a furnace, a reciprocable grate, a bracket mounted on a wall of the furnace, said bracket having arms extending from both sides thereof and positioned with one arm extending into the furnace upon which the bracket is mounted, and the other extending outwardly from the furnace, a thermostat carried by the arm extending into the furnace and positioned to be located below the grate, a vertically disposed lever pivotally mounted on the arm extending outwardly from the furnace, power drive mechanism, linkage between said mechanism and grate to reciprocate the latter, a movable controller bar movable in one position to disengage the drive mechanism from the linkage, the vertically disposed lever having an adjustable connecting between its lower end and the thermostat in the furnace, the upper end of the lever having a knee action joint therein with resilient means for resiliently retaining the parts in alignment, the upper end of the lever being in alignment with the controller bar when the thermostat is in hot position to disengage the drive mechanism, and out of alignment therewith on the cool position of the thermostat to permit engagement of the drive and reciprocation of the grate.
